METHOD OF AND APPARATUS FOR HEAT
REGULATION FOR BUILDINGS

Alexander J. Lewis, Chicago, Ill.

Application June 2, 1933, Serial No. 674,030

9 Claims. (Cl. 237—12)

My invention relates to heat regulation and particularly to a novel system whereby economical and efficient operation are secured.

The item of cost of heating large buildings is a substantial one and my invention has for its object the provision of a system, substantially automatic in operation, by which efficient heating may be secured at all times under all temperature conditions. The system assumes heating by steam although the principles could be applied to heating by other mediums; it assumes also the operation of respective steam valves by air motors and this may be varied as required. It is illustrated in connection with a large building in Chicago in which the system is in operation, the building containing a highly diversified series of activities. For example, offices, stores, a theatre, club rooms operated some in the daytime and some at night or both, a broadcasting station with numerous studios, etc. The building is forty-three stories in height and occupies a large ground area.

The general objects sought and obtained in the system herein described are:

25 *First*.—A division of the building into three operative sections called for convenience the main section, the intermediate section and the tower section.

30 *Second*.—The placing of the steam supply risers in each section in reasonable closely spaced relation, numbering the risers consecutively in each section and then supplying steam to adjacent risers alternately at longer or shorter intervals depending upon requirements and conditions.

35 *Third*.—The use of time controlled mechanism for automatically effecting alternate steam supply to the risers, said mechanism being selective as to periods of time and character of control.

40 *Fourth*.—The provision of an outdoor thermostat adapted to vary the time lengths for steam supplied to the alternate risers according to outdoor temperatures.

45 *Fifth*.—The provision of manual control for any riser or series of risers, so arranged that independent operation of one series of risers will not interrupt or change the operation for the remainder of the building.

50 *Sixth*.—The provision of signal means to the boiler room to operate a sufficient time in advance of a contemplated change in steam needs, thus avoiding excessive load fluctuations and maintaining the coal consumption curve in substantially exact parallelism with the outdoor temperature curve during normal operation.

55 The system as above described in general is

electrically operated so far as the timing elements and thermostatic control are concerned. The electrically controlled circuits serve to operate motors that actuate various air valves that in turn operate the steam valves.

60 It will be understood that the system contemplated herein does not include means for thermostatic control of the temperature of individual offices, stores or other working spaces; that control is left to a different system and apparatus.

65 My system is intended to control the means for making heat available to the different individual regulations and is operated so as to furnish steam according to expected requirements. For example, during non-working periods, it is not ex-

70 pected that the occupants of different spaces will reset the controlling thermostats for a low temperature, and in the absence of a system such as mine a great amount of steam would be wasted during such periods. Manual control cannot be

75 relied on because of the uncertainty of the human element. Furthermore, during comparatively mild weather, say 45° to 60°, the individual working spaces may require heat only at long intervals;

75 yet if steam is constantly supplied to all the mains it results in a high ratio of loss through radiation in the service pipes. In such mild weather, I have found that by furnishing steam alternately to adjacent risers or mains the lateral radiation therefrom into the adjacent spaces will materially

80 reduce the requirement for direct steam in such hours.

85 The system will be more readily understood by reference to the accompanying drawings in which:

90 Fig. 1 is a fragmentary elevation diagrammatic in form showing the application of the system to a building of a character in which three sections are provided.

95 Fig. 2 is a wiring diagram;

Fig. 3 is a continuation of Fig. 2 and when placed immediately above Fig. 2 with the different wires in register shows a complete wiring diagram for the system.

100 Fig. 4 is a diagram of a single circuit taken from the main diagram, for greater simplicity of description.

105 Fig. 5 is a diagrammatic elevation of one of the control boards for one of the sections of the building;

110 Fig. 6 is a similar view of the board for a second section;

Fig. 7 is a detail showing the method of operation of an air valve by the motor;

- Fig. 8 is a detail showing the form of the rocker arm forming a part of the reversing switch;
- Fig. 9 is a fragmentary side elevation of the discs mounted on the time controlled shaft;
- Fig. 10 is a view taken at right angles thereto;
- Fig. 11 is a side view of a notched disc used for half-hour-on, half-hour-off operation;
- Fig. 12 is a similar view of a disc arranged for one-hour-on, two-hour-off, and
- Fig. 13 is a similar view of the disc used for signalling and Sunday operation.
- In Fig. 1, I have shown a building having stores 10, offices 11, a theatre 12, and divided into three heating sections, for example, section A which is called the main section, section B called the intermediate section, and section C called the tower section. Each section has a plurality of risers indicated at 13^x, 13, 14, 15 and 16 in section A, at 17 and 18 in section B and at 19, 20, 21, 22, 23 and 24 in section C, the latter being fed downwardly from a main 25 through a high pressure riser 26. The main section and master control board is indicated at D, the intermediate control board at E and the tower control board at F. The control boards E and F are shown in Figs. 5 and 6 respectively. The master control board carries two motors 27, 28, the control board E contains two motors 29, 30 and the control board F carries two motors 31 and 32.
- In Fig. 4 I have shown three typical notched discs 33, 34, 35 that are mounted on a common shaft 112 shown in Figs. 9 and 10. This shaft is operated by timing mechanism (not shown) so arranged that the shaft and likewise each disc, has one complete revolution each twelve hours.
- It will be noted that the discs 33, 34 each have six projections or elevations and that the rocker arms 38, 39 are mounted in such position that the clockwise rotation of the discs will cause each rocker to be oscillated six times for each revolution—that is, six times every twelve hours or every two hours. However, the discs are set in staggered relation on the shaft 112 and in consequence one of the rockers 38, 39 is actuated each hour.
- The disc 35, has twelve elevations and therefore the rocker 40 will be actuated 12 times for each revolution or once each hour. However, the disc 35 is set on the shaft 112 in such position that its elevations occur at points midway between the elevations on the two discs 33, 34; that is, an end view of the assembled discs 33, 34, 35 would show 24 projections in the circumference, one for each half hour.
- It should be understood that these notched discs are typical only, and are used for certain simple operations known as "one-hour-on—one-hour-off" and "half-hour-on—half-hour-off."
- These periods may be and are varied widely to suit different building arrangements and requirements. Further it should be understood that the multitude of operations hereafter described and shown in the main diagram are carried out by means of similar appropriate discs all mounted on the same shaft 112. In Figs. 11, 12 and 13 I have shown other specimen discs, a description of which will be furnished at a later point in the specification.
- Each of the rocker arms 38, 39 and 40 is so mounted that when it is raised at the end that rides on the notched disc it will serve to close a contact and complete a circuit. For example, in order to trace the circuit it will be assumed as shown in detail in Fig. 4 and in the full diagram of Fig. 2 that each of the rocker arms has a connection to a wire 36 from a source of electrical power, this being controlled through a switch 37.
- With the rocker arm 39 in switch closed position the current flows through the wire 41 through the knife switch 42 closing contacts 43, 44, then through the wire 45 to the relay 46 and thence to the return wire 47. The action of the relay serves to close a circuit in which the feed wire is indicated at 48, the current passing through the closed contacts 49 to the wire 50 and to the two contacts 51, 52. When the knife switch 53 is in upwardly closed position this serves to energize the wires 54, 55 to the motors 27, 28 respectively, through an appropriate reversing switch 54^a, 55^a in Fig. 2. The circuit is completed through the motors 27, 28 and through the wires 56, 57. This will serve to operate both motors 27, 28 but in reverse directions. Likewise, when the disc 33 is rotated to position to cause the rocker arm 38 to close its switch, the current flows through the wire 65, switch 42, then (if the switch is in upper closed position) through wire 45 to relay 46 with the result already described. With the switch in upper closed position, it is assumed that a reversal of the motors has taken place at the 30 minute period intervening between the one hour alternate operation by the discs 33—34. However, with the switch 42 in down closed position, the action of the disc 33 will be to complete a circuit through relay 61 instead of relay 46, this being necessary as the intervening 30 minute reversal has been discontinued. The result of the operation of motors 27—28 will be described later.
- Assuming that the knife switch 42 is in lower closed position and that the time shaft 112 is operating as described, the operation will actuate the motors 27, 28 at one hour intervals, that is the motors will be operated simultaneously but in reverse directions once each hour. This because the contact point 60^a in the knife switch 42 is dead, and no actuation takes place as the result of the rotation of the disc 35. If however, temperature conditions require more heat than will be supplied by one-hour-alternate operations, the knife switch 42 is closed in its upper position in which position the circuit controlled by the disc 35 will be placed in operation and the wire 59 will be energized every hour. However, this disc 35 is placed with its projections in staggered relation to the projections on the discs 33, 34 and an actuation resulting in a simultaneous operation in reverse directions of the two motors 27, 28 will occur every half hour.
- The operation of closing the contact controlled by the arm 40 results in energizing the wire 59, thence through the knife switch 42 and the contact 60 through the relay 61 and out through the return wire 47. The action of the relay 61 serves to energize the wire 62 then through a knife switch 53 to wires 63, 64 to the other sides of the motors 27, 28 for reverse operation. This action will occur thirty minutes after the operation previously described. The next successive action will be as the result of the operation of the disc 34 through the described circuit and thirty minutes later, the disc 35 will again operate the parts.
- When the switch 53 (Fig. 4) is in the down closed position the clock operation is discontinued and the control is manual by means of the hand switches 66, 67. In any event the lamps indicated at 68, 69 are lighted through the appropriate circuits when the motors 27, 28 have been 148

operated to a position in which the steam is on different risers controlled by the motors. Referring to Fig. 2, assume the motor 27 has operated to turn on steam in the risers controlled thereby, and that motor 28 has operated to turn off steam in its risers, at the completion of the cycle the reversing switches associated with each motor will be re-set in such a position that the switch 54^a will be closed and the switch 64^a will be opened. Current will then pass from wire 56, through wire 71 and the switch 54^a to the wire 69^a and the lamp 69; thence through wire 69^b and relay 105 to the wire 105^a from the ground. On a reversal of operation the switch 54^a will be opened and switch 64^a closed whereupon current will flow through wires 57-70, switch 64^a and wire 68^a to lamp 68, thence through wire 68^b and relay 105, the ground as described.

The circuit described covers the operation of motors 27, 28 that are mounted on the master board. However, these motors have no function in connection with the master board as they merely operate a series of air valves that control the risers in the main section of the building, for example, the section A in Fig. 1. Similar pairs of operating motors are mounted on the auxiliary boards E, F that are located in different sections of the building. These motors with the appropriate wiring diagrams are shown in Figs. 5 and 6 and as the circuits are the same and the functions of the motors are the same in each case we will describe the circuit only in connection with Fig. 5.

The wires X-1 to X-7 inclusive are continuations of the wires correspondingly numbered in the main diagram of Fig. 2, while the wires Z-1 to Z-7 are operating wires for the board F and correspond to the similarly lettered wires in Fig. 2.

Referring to Fig. 5 which is a diagram of the board E controlling the intermediate section of the building. I have correlated this diagram with the main diagram shown in Fig. 2 by lettering the corresponding wires on the two figures X-1 to X-7 inclusive. Wires X-1 to X-4 inclusive lead to the binding posts at the lower portion of the knife switch 53^a in Fig. 2. As indicated on Fig. 5 the wire X-1 corresponds in function to wire 64; the wire X-2 to 55, etc. In order to explain the function of the wire X-1, assume that the relay 61 has been energized by the action of a time disc. Current then passes through the contacts closed by the relay, then through the wire 62 to wire 130, then through contacts 131 of relay 86, then through wire 132 through a pair of contacts on the knife switch 53^a thence by the wire X-1 to the motor 30 shown in Fig. 5 passing through the reversing switch 30^a, thence out through the wire 30^b to wire X-7 which is the return wire.

Wire X-2 functions when relay 46 is closed. Current then passes through its contacts by the wire 50 to contact 50^a in the knife switch 53^a, thence over the wire X-2 to motor 29 in Fig. 5 through reversing switch 29^a, thence out through wire 29^b to wire X-7.

When relay 61 is closed, the current passing through wire 62 contact 62^a in the knife switch 53^a will conduct current through wire X-3 to motor 30 in Fig. 5, through reversing switch 30^a, thence through the motor and out through the wire X-7. Likewise when relay 46 is closed current will pass through contacts 49 over wire 50 thence through contact 133 of relay 86, then through wire 134, contact 51^a of knife switch

53^a, thence outward through wire X-4 to motor 29 in Fig. 5. Wires X-5, X-6 operate through the reversing switches shown in Fig. 5 to energize the lamps 68^a, 69^a shown in Fig. 2.

Wire Z-1 shown in the arrangement of board F in Fig. 6 functions as follows: With the closing of relay 46 current passing through the contacts and wire 50 passes through contacts 135 of relay 86, thence through wire 136 and through contact 50^b of knife switch 53^b, thence through wire Z-1 to motor 32 in Fig. 6 through reversing switch 32^a, thence out through wire 32^b to return wire Z-7. The closing of relay 61 causes current to pass through wire 62, then through the switch 53^b to wire Z-2, then through motor 31 reversing switch 31^a and out through return wire Z-7. The detail of wires Z-3, Z-4 and Z-5 and Z-6 should be readily understood from the preceding description.

It should be understood that the system shown in the diagram contemplates the operation of three units or sections, and that each unit includes two motors 27 and 28, 29 and 30, 31 and 32, all of them operating simultaneously by operation of the timing discs heretofore described. The number of sections or divisions might be multiplied or reduced, the only difference in the wiring being the addition or subtraction of duplicate mechanisms.

All operations heretofore described are performed by three discs shown in Fig. 4 and illustrated diagrammatically by the series of concentric circles at the center of Fig. 2. These circles with the dots and connecting lines are intended to indicate the provision for half hour operation, the figures surrounding the outer circle being intended to represent a twelve hour period of a day. The wire 36 leading to the center of the circles is the common power wire such as shown under the corresponding number in Fig. 4, while the numbers 41, 59 and 65 are corresponding wires leading from the contacts actuated by the rocker arms that engage the respective discs 34, 35 and 33. Thus with only three discs the various sections of the building may be caused to operate alternately at half hour intervals or at one hour intervals, but the system contemplates a much more elaborate method of control by the use of a relatively large number of discs, each controlling an appropriate rocker and an electrical circuit. Therefore, in order to avoid confusion a diagram of the various disc controls has been placed to the right of the central diagram, this supplemental showing consisting of a plurality of circles with dots thereon, each dot indicating a contact that is successively made due to the rotation of the disc by the timed shaft 112.

In the supplemental diagram a common power wire similar to wire 36 is indicated at 72. Mounted on the time shaft 112 as shown in Fig. 9 are a large number of discs, each one of which has projections that correspond to a dot in the diagram. It being understood that when the disc rides to a point at which contact is made with the wires shown a circuit will be closed through the wire 72 and the corresponding connected wire.

When an appropriate disc rotates to a point to close a contact and energize the wire 73, it serves to light a lamp 74 in the boiler room; this is an action that takes place at a predetermined time before steam is to be required for a certain specified operation. By reason of the closing of an adjacent contact the wire 75 is also energized which serves to ring a bell 76 in

the boiler room, thus notifying the engineer in advance of automatic operations that may lessen or increase the need for steam. The next operation that takes place is the closing of a circuit 5 through the wire 77 which passes through the knife switch 78, contacts 79, then through the wire 80 over to the relay 46, following which a motor actuation operation occurs as heretofore described. As the discs rotate, the next operation 10 will be the closing of a contact and energizing the wire 81 which likewise passes through the knife switch 78, thence through the wire 82 to the relay 61 effecting a reversal of motor operation as heretofore described. As shown these 15 operations take place at relatively long intervals, in order to furnish only enough heat to prevent freezing in the building. For example, the spacing of the contacts controlling the wires 77—80 indicates a period of about 45 minutes; further, 20 it will be noted that the wires of contacts 77—80—83^a—87^a—88^a, are repeated so that the sequence takes place 3 times during each 12 hour period. Thus, as described, the operation would result in 45 minutes on and 4 hours off for alternate 25 risers. This, as previously stated, is a matter of selection, the appropriate disks for any desired sequence of operation being placed on the time shaft 112. In order to automatically take the system out of normal control for Sunday and 30 holiday operation, the switches 84, 78 will be closed at the proper time and a contact 83^a will be closed to energize the wire 83 which serves to operate the solenoid switch 85. This serves to open the various switches mounted on the arm 35 and to break the circuits in all of the "on" 35 wires; in other words, the wires through which the motors might otherwise be caused to operate to turn on the steam. Further travel of the discs results in closing a contact 87^a and energizing 40 a wire 87 which leads through the knife switch 78 and energizes the relay 61, but the operation of energizing the operating motors is effective only on one motor to turn off the steam control the other motor being inactive due to the opening 45 of the switch 86. Further travel results in closing a contact 88^a and energizing the wire 88 which through the knife switch 78 energizes the relay 61 and effects a further motor operation in the event that any of the motors may have been on 50 and not turned off by the preceding operation. The last three operations take place in rather close sequence. Of course, when the knife switch 78 is open, none of the operations just described will take place. This switch is placed in operative position for Sunday and holiday operation 55 when it may be necessary to furnish heat at intermittent intervals to avoid freezing.

In order to effect automatic control according to outdoor temperatures, I provide apparatus, a 60 diagram of which is shown in Fig. 3 comprising a thermostat 89, shown diagrammatically as providing an arm 90, having a power connection through the switch 91 to the wire 92. When the thermostat arm makes contact at the point 65 marked 45° current will be supplied through the wire 93. This will energize the solenoid 94 and close the contacts carried by the arm 96 the ground being established through the wire 95. It is assumed that when outdoor control is desired, the switch 42 is in open or neutral position, as shown in Fig. 2.

The action of the solenoid 94 serves to move the contact pieces to the left in Fig. 3, the closing of the contact 96^a energizing a wire 92^a and lighting a lamp 92^b.

Referring now to Figs. 2, 3, and 4, and following the power wire 36, which is the common supply for the clock discs, it will be seen that when the disc 34 has rotated to a point as shown in Fig. 4 where the contact is closed and wire 41 is energized, this serves to energize wire 97, Figs. 2 and 3, thence through contact 96^b, wire 96^c to wire 104. This wire, Fig. 2, leads through relay 46, closing contacts 49, and energizing wire 50; thence through contacts 52 in the switch 53, and wire 55, to the motor 28. The wire 50 is common to the other switches 53^a—53^b and the motors of the auxilliary control boards are likewise actuated. One half an hour later the disc 35 will close a contact and energize a wire 59, Fig. 2 and this energizes wire 99, Fig. 3, thence through contacts 96^d and wire 96^e to wire 103. This wire energizes the relay 61 and energizing wire 62, thence through the switch 53 and wire 63 to motor 27; in other words, this results in turning on heat in the risers controlled by the motor 27 and turning off the heat in the risers controlled by the motor 28, at 30 minute intervals.

Thirty minutes later, the disc 33 will move to a position to close a contact and energize wires 65 and 98, thence through contacts 96^f and wire 96^c to wire 104, whereby relay 46 is operated with the result already described. Thus with the temperature outdoors at 45° the operation will be 1/2 hour on and 1/2 hour off, throughout the building.

However, should the temperature rise to 55°, the thermostat arm 90 will make contact and energize wire 100, thus energizing solenoid 101 and closing the switches 102. The contact 102^a lights a lamp 102^b. The closing of the contacts 102^c—102^d enables the wires 103—104 to be energized by the closing of contacts by the discs 33—34, through wires 65—41 and 98—97, resulting in alternation at one hour intervals. However, while the disc 35 will close a contact to energize wires 115 59—99, the contact 102^e is incomplete and there is no actuation of the motors at the 1/2 hour interval.

Assuming that the temperature rises to, say 62° outside of the building, the thermostat arm 120 90 will close a contact to energize the wire 137 shown in Fig. 3 and at the upper right hand corner of Fig. 2, and this will act even though the switch 84 is open, to energize the solenoid 85, and to open the switches 86. This contact in the 125 thermostatic switch, indicated at 138 will continue through further travel of the arm 90 toward a higher temperature, and at a further half degree increase, will serve to close a contact and energize a wire 139 which likewise energizes wire 130 104. Further travel over a half degree range will close a contact and energize a wire 140 which is connected to the wire 103, the effect following the energizing of wires 103 and 104 being described in the preceding matter. The effect however, is 135 to shut down all motors and discontinue the supply of heat to the building.

In order that the boiler room may have information at all times when steam is required, it will be noted by reference to Fig. 2 that I provide a 140 relay circuit 105 in series with the lamp circuits 70, 71, etc. Therefore, whenever any lamp is energized the relay will be closed and current will pass through the wire 106 to a lamp 107 in the boiler room.

As an added precaution against misoperation in the event that an electric clock is used as the time element for operating the discs, I provide means such as shown in Fig. 2 consisting of a circuit 108 containing a relay the 145 150

action of which maintains the switch 109 in open position at all times when there is current in the lines. However, in the event of failure of the current switch 109 will close and current through 5 a separate circuit 110 serves to ring a bell 111, thus notifying the attendant that the time device has temporarily discontinued operation.

In Figs. 9 to 13 inclusive I have illustrated the details of the time controlled mechanism shown 10 in the diagram in the preceding figures. In those figures I illustrate a shaft 112 so connected as to rotate once in twelve hours by a clock, not shown. On this shaft is mounted a plurality of discs, the number and configuration of which 15 will depend on the requirements of operation. For example, in Fig. 11, I have shown a disc 113 having 12 notches such as shown at 35 in Fig. 4. In Fig. 12, I have shown a disc 114 having notches arranged at one hour and one-hour—two-hour 20 intervals. In Fig. 13 I have shown a disc 115, a plurality of which are used as signalling discs and Sunday and holiday circuits described by the numerals 72 to 88. The discs and shaft are mounted on a suitable frame and the operating 25 arms 116 are pivoted thereabove in the proper position above the contact elements 117. This arrangement provides for practically unlimited selection of time intervals according to needs in each case.

30 The description up to this point has been of the electrical control for the various operations. The motors that are electrically actuated have the function of operating air valves through which steam is supplied to or shut off from the 35 various risers. As shown in Fig. 5 and duplicated in the other boards, the motor shaft 118 has a worm 119 engaging a worm wheel 120. This wheel carries a pin 121 which engages a yoke 122 best shown in Fig. 8, and connected to the reversing switch 123. The contacts opened and 40 closed by this switch are shown in the diagram of Fig. 2. In each case where one set of contacts is closed as in Fig. 8 the contacts in the signal light circuit are likewise closed.

45 The worm wheel 120 is carried on a shaft 124 which operates an air valve 125 in the air manifold 126 which leads to the various individual air valves 127 on the adjacent board. Each of the air valves 127 controls the admission of air to 50 the diaphragm operated steam valve of a riser. The various air-operated steam valves in the risers may be of the type that is closed by air pressure and opened by a spring. Thus the hand valves 127 will normally be in a position to permit 55 the air to flow through the same to the steam valves. When, however, it is desired to manually open the steam valves of any riser, the handle 128 of the proper valve 127 is turned to close the valve to the supply of air and to exhaust the air in the line to the steam valve, thus permitting 60 the steam valve to be opened by its spring. Preferably the valves and the risers will be numbered consecutively and the operation of the motors will serve to alternately turn on and off 65 the adjacent risers.

Referring to Fig. 1 and to the control board D indicated diagrammatically, it will be seen that when the motor 27 is actuated air from a source of supply through the pipe 125^a will be delivered 70 to the manifold 126 and thence to the air valves. The pipes from the air valves are indicated in double lines. The diaphragm operated valves in the risers are lettered 13^x^a, 13^a, 14^a, 15^a and 16^a in the risers that are lettered 13^x, 13, 14, 15 and 75 16 and the air valves on the board are correspond-

ingly lettered. Thus when the motor 27 operates to admit air to the manifold 126 the air valves 13^x^a, 14^a and 15^a will be operated to admit steam to the alternate risers. Correspondingly when there is a further actuation the motor 27 will operate to shut off those air valves and open the air valves 13^a and 15^a.

Correspondingly, referring to the intermediate section control board E, when on motor operates it will admit air to valve 17^a which will admit steam to riser 17. When the opposite actuation takes place, this valve will be shut off and valve 18^a will be opened admitting steam to riser 18. The corresponding action takes place in connection with the tower section controlled by the board F, the valves being correspondingly numbered.

It will be understood that the illustration in Fig. 1 is wholly diagrammatic and is intended merely to show the capacity for alternate supply of heat to adjacent risers. This is likewise true as to Figs. 5 and 6 which serve to show the wiring diagram and the air pipe diagram. A detail of board D has not been included as it is in effect practically a duplicate of board F shown in Fig. 6.

While I have illustrated the operation by means of a reversing electric motor which is used for operating master air valves, it will be understood that other forms of motors may be used instead.

In operation assuming the installation of the system and the division of the building into appropriate sections, the engineer will select suitable notched discs and by the removal of the shaft 112 place the discs on the shaft in proper relation. For example, if he wishes to provide for one-hour-on—one-hour-off, and half-hour-on—half-hour-off, he will place on the shaft discs such as shown at 33, 34, 35 in Fig. 4. He will likewise select discs to provide for night or Sunday and holiday operations, such as shown in Fig. 12, that is, two-hours-off, half-hour-on. He will also select discs for performing the signalling operations such as operated by the wires 73, 75, etc. After placing the selected discs on the shaft and starting the clock, the continued operation is all controlled by the operation of the switch 42 which selectively provides for hour or half hour alternation; by the switch 78 which places the building under night or Sunday and holiday operation and by the switches 53, 53^a, 53^b which enable the control by manual operation. He may further control any riser or series of risers manually by means of the air valves.

The operative periods described are selected merely as simple examples; actually, the periods used by the applicant in practice are such as 20 minutes on—one hour off; half hour on, two and one half hours off, etc. Of course, if the heat dissipation at the point of use was constant, there would be no difference between one hour on—one hour off, and half hour on—half hour off; actually, however, the radiators at the point of use are controlled by a room thermostat and under some temperature conditions the room thermostat would call for heat during, say, 45 minutes of each hour; obviously, therefore, if the heat was off a full hour there would be a period where heat was required and none available; and this would not occur during half hour on—half hour off operation. However, it is practically inevitable that any space to be heated is served by two or more risers, one of which will be furnishing steam when another is shut off. This serves to

modify somewhat the effect described in the preceding portion of this paragraph.

In general, the operation will have been understood from the preceding description. It may be well to add however, that the system is extremely flexible in that it provides for any possible need in a building having diversified activities without excessive heat loss by supplying it to points where it is not needed; it provides for individual operation of any riser or series of risers; it provides for Sunday and holiday operation, and, by means of the outdoor thermostat, insures against inefficient operation by supplying heat when it is not needed, although avoiding the danger of too low temperatures in the building in the event of a sudden temperature change; it provides for night operation by which steam may be supplied sufficiently to prevent undue lowering of temperatures and it provides for individual supply of adequate heat to offices, stores or club rooms that remain open during the night.

It will be understood that in real winter weather the described system will not be used during working hours because it will be necessary to deliver steam to all of the risers at all times. However, at night or on Sundays during such weather the system will be put in operation. During working hours in cold weather switch 78 will be open, switch 42 will be open and switch 53 will be in down-closed position. In milder weather, during working hours, the switch 78 will be open, the switch 53 in upper-closed position. If half hour alternation is desired, the switch 42 will be closed in upper position and if one hour alternation or some other longer time interval is needed, the switch 42 is closed in down position. On Sundays or holidays the switches 53 are closed in up-position, the switch 42 open and the switch 78 closed. This will put the control under the outdoor thermostat.

If the engineer wishes to take any section out of automatic control the respective switch 53, 53^a, 53^b is closed in down position thus placing the section under manual control.

If with the whole building on night operation any particular office or section requires heat, the required hand valves 128 may be operated thus taking the corresponding risers out of automatic control and furnish a constant supply of heat.

The term "adjacent" in the claims as a definition of the relation of the respective risers, is used in its broad sense, such as contemplated by the terms "near" or "neighboring" and not necessarily in the sense of "adjoining" or "contiguous."

I claim:

1. The method of heat regulation of buildings which are provided with valves for controlling individual heat supply risers, which consists in automatically alternating the supply of heat to adjacent risers according to a predetermined time interval.

2. The method of heat regulation of buildings which are provided with valves for controlling individual heat supply risers, which consists in automatically alternating the supply of heat to adjacent risers according to a predetermined time interval during working hours and then automatically alternating the supply of heat to said risers at a different time interval during non-working hours.

3. The method of heat regulation of buildings which are provided with valves for controlling individual heat supply risers, which consists in automatically alternating the supply of heat to adjacent risers according to a predetermined time interval during working hours and then automatically alternating the supply of heat to said risers at a different time interval during non-working hours and manually segregating any risers from said automatic control during any period. 80 85

4. The method of heat regulation of buildings which are provided with valves for controlling individual heat supply risers, which consists in automatically alternating the supply of heat to adjacent risers according to a predetermined time interval, and continuously testing outdoor temperatures and automatically varying said time intervals according to said outdoor temperature variations. 90 95

5. The method of regulating the supply of heat to relatively large buildings having individual valve control for each heat supply riser and divided into a plurality of heating sections, with the controls for each section in closely adjacent relation, which consists in automatically alternating the supply of heat to adjacent risers according to a predetermined time schedule, and providing for control of groups from a central point. 100 105

6. The method of regulating the supply of heat to relatively large buildings having individual valve control for each heat supply riser and divided into a plurality of heating sections, with the controls for each section in closely adjacent relation, which consists in automatically alternating the supply of heat to adjacent risers according to a predetermined time schedule, and providing for control of groups from a central point, then automatically varying said time schedule according to outdoor temperatures. 110 115

7. A heating system for large building, comprising in combination, a plurality of adjacent risers, valves for each riser, motor actuated means for simultaneously turning on the valves of certain risers and turning off the valves on adjacent risers, and time controlled means for effecting the operation of said motors according to a predetermined schedule. 120

8. A heating system for large buildings, comprising in combination, a plurality of adjacent risers, valves for each riser, motor actuated means for simultaneously turning on the valves of certain risers and turning off the valves on adjacent risers, time controlled means for effecting the operation of said motors according to a predetermined schedule during normal working hours, and means for operating said time controlled mechanism on a different schedule for non-working hours. 125 130 135

9. A heating system for large buildings, comprising in combination, a plurality of adjacent risers, valves for each riser, motor actuated means for simultaneously turning on the valves of certain risers and turning off the valves on adjacent risers, time controlled means for effecting the operation of said motors according to a predetermined schedule, an outdoor thermostat, and means operable thereby for varying said time schedule according to outdoor temperature. 140 145

ALEXANDER J. LEWIS.
